Fig. 1.

UNITED STATES PATENT OFFICE.

WILLIAM H. WAKEFORD, OF BALTIMORE, MARYLAND.

ROLLER GRINDING-MILL.

SPECIFICATION forming part of Letters Patent No. 321,551, dated July 7, 1885.

Application filed September 11, 1884. (No model.)

To all whom it may concern:

Be it known that I, WILLIAM H. WAKEFORD, a citizen of the United States, residing at Baltimore, in the county of Baltimore and State 5 of Maryland, have invented certain new and useful Improvements in Roller Grinding-Mills; and I do hereby declare the following to be a full, clear, and exact description of the invention, such as will enable others skilled in the 10 art to which it appertains to make and use the same.

This invention relates to that style of roller grinding-mills in which the successive breaks or pairs of rollers are arranged in one and the 15 same horizontal plane.

My invention consists of a certain combination, with the adjustable rollers, of chain-wheels and drive-chains, whereby the motion of the first adjustable roller is transmitted to the succeeding adjustable rollers. This means for 20 transmitting motion to some of the adjustable rollers presents the same facilities for adjusting the rollers as belt-gearing, but is far superior to the latter in the respect that the speed 25 of the adjustable rollers will remain uniform under all adjustments, because a drive-chain admits practically of no slippage, whereas there is apt to be more or less slippage where a driving-belt is used, even when a belt-tightener is applied to it—an adjunct not required 30 by the drive-chain. The use of cog-gearing is more objectionable than belt-gearing, because by the adjustment of the rollers the cog-gears are apt to be thrown out of line more or less, 35 so that they cannot run true and will soon wear out.

In order that my invention may be clearly understood, I have illustrated in the annexed drawings and will proceed to describe so much 40 of a roller grinding-mill of the type referred to as will suffice to show the practicable application of my invention.

Figure 1 is a plan view of such a roller grinding-mill. Fig. 2 illustrates the same parts 45 partly in end elevation and partly in cross-section on the line $\alpha\alpha$ of Fig. 1.

The same letters of reference indicate identical parts in both the figures.

I have shown a mill having three breaks or 50 pairs of grinding-rollers, of which the non-adjustable rollers A, B, and C are all secured

to a single shaft, D, the pulley D' on one end of which is driven by the belt from pulley E' on the corresponding end of the counter-shaft E of the mill. A pulley, E², on the opposite end of the counter-shaft drives, by cross-belt, the pulley C³, fixed on one end of the shaft C² of the adjustable roller C. To the other end of the shaft C² of the adjustable roller C³ a chain-wheel, C⁴, is secured. Chain-wheel C⁴ drives a chain-wheel, F⁵, by means of the drive-chain F. Chain-wheel F⁵ is constructed with two sets of sprockets—one for the drive-chain F and the other for the drive-chain G—by which the motion of the chain-wheel F⁵ is transmitted to a chain-wheel, B⁶, on one end of the shaft B² of the adjustable roller B'. The shaft of adjustable roller B' transmits motion 60 to the adjustable roller A' by means of the chain-wheel B⁷, drive-chain H, sprocket-wheel H', drive-chain I, chain-wheel A⁸, and roller-shaft A⁹.

I have shown the sprocket-wheels F' and H' as journaled in bearings on top of the main frame of the mill; but it is obvious that the location of these chain-wheels may be changed to suit circumstances or the views of the builders.

I have shown screws for sliding the bearings of the adjustable rollers to effect the adjustment of the latter; but any other known means for adjusting the adjustable rollers of roller grinding-mills may be employed. The ordinary slack in the drive-chains is so little varied by the slight adjustments of the adjustable rollers as not to affect the driving action 85 of such drive-chains.

I claim as my invention—

In a roller grinding-mill the breaks of which are arranged in one and the same horizontal 90 plane, the combination, substantially as before set forth, with the adjustable roller of one succeeding break, of the chain-wheels and drive-chains for transmitting the motion of one 95 adjustable roller to the other adjustable roller.

In testimony whereof I affix my signature in presence of two witnesses.

W. H. WAKEFORD.

Witnesses:

C. A. NEALE,
E. T. WALKER.
